(57) **CLAIM**

The ornamental design for a payment card chip, as shown
and described.

DESCRIPTION

FIG. 1 is a front left perspective view of a payment card chip
showing our new design; and,

FIG. 2 is a front elevation view thereof.

The broken line showing of a card depicts environment and
forms no part of the design claim.

The broken lines shown on the chip represent unclaimed
features of the payment card chip and form no part of the
claimed design. The dot-dash lines around the chip represent
the bounds at which the claimed portion of the chip surface
terminates, and form no part of the claimed design.
